(57) **CLAIM**

The ornamental design for the driving bit head for manual and powered screwdrivers, as shown and described.

DESCRIPTION

FIG. 1 is a perspective view of the first embodiment of a driving bit head for manual and powered screwdrivers, showing the new design;

FIG. 2 is an enlarged perspective view of the tip of the driving bit head for manual and powered screwdrivers;

FIG. 3 is another perspective view of the driving bit head for manual and powered screwdrivers;

FIG. 4 is a first side view thereof;

FIG. 5 is a second side view thereof;

FIG. 6 is a third side view thereof;

FIG. 7 is fourth side view thereof;

FIG. 8 is a bottom view thereof; and

FIG. 9 is a top view thereof.

FIG. 10 is a perspective view of the second embodiment of a driving bit head for manual and powered screwdrivers, showing the new design;

FIG. 11 is an enlarged perspective view of the tip of the driving bit head for manual and powered screwdrivers;

FIG. 12 is another perspective view of the driving bit head for manual and powered screwdrivers;

FIG. 13 is a first side view thereof;

FIG. 14 is a second side view thereof;

FIG. 15 is a third side view thereof;

FIG. 16 is fourth side view thereof;

FIG. 17 is a bottom view thereof; and,

FIG. 18 is a top view thereof.

The broken lines in the drawings illustrate portions of the driving bit head for manual and powered screwdrivers and form no part of the claimed design.
